ROLL-CHANGING APPARATUS FOR ELECTROLYTIC COATING LINES

Clarence J. Klein, Hollidays Cove, W. Va., assignor to National Steel Corporation, a corporation of Delaware

Application February 10, 1944, Serial No. 521,796

5 Claims. (Cl. 212—134)

This invention relates to electrolytic coating lines and, in particular, to means for changing contact rolls installed therein for engaging the strip being coated to connect it to one terminal of a source of electric current.

In one form of electrolytic tinning line (disclosed and claimed in application Serial No. 487,758, which E. W. Rieger and I filed on May 20, 1943), a plurality of electrolyte pans or tanks are disposed in spaced relation in upper and lower tiers and a strip is passed through the electrolyte in the pans of the two tiers successively, where it is first coated on one side and then on the other. The pans of the upper and lower tiers are carried on common supporting columns. Contact rolls are disposed between adjacent pans of both tiers, and are journaled in spaced housings. In the operation of electrolytic tinning lines, it is observed that accretions of tin initially deposited on the strip build up on the surface of the rolls. This necessitates redressing of the rolls about once a week. The construction of the tinning line as outlined above, however, precludes the use of the mill crane for handling the contact rolls of the lower tier of pans because of the presence of the upper tier of pans thereabove with their contact rolls and supporting structure. As a result, the periodic changing of the contact rolls associated with the pans of the lower tier has been attended with considerable difficulty. The necessity of stopping the strip traversing the tinning line while changing contact rolls is seriously objectionable.

I have invented a novel lifting apparatus for handling the contact rolls associated with the electrolyte pans, so they can be removed from and replaced in their supporting housings easily and quickly and without seriously interrupting the production of tinned strip. In a preferred embodiment, I provide an overhead rail or track extending transversely of the tinning line and laterally thereof to a point substantially free from overhead obstruction. A trolley traveling on the track is equipped with a hoist for lifting a contact roll out of its housings. When the roll has been raised clear of the housings, the trolley is moved along the rail and the roll is deposited on any suitable support in a region at one side of the line which is accessible to the mill crane. The reverse of this procedure is followed in placing a redressed roll in position.

Further details, novel features and advantages of the invention will become apparent from the following description thereof which refers to

the accompanying drawings illustrating the preferred embodiment. In the drawings,

Figure 1 is a partial transverse section through a tinning line having the invention incorporated therein, with parts removed; and

Figure 2 is a partial longitudinal section taken along the plane of line II—II of Figure 1.

Referring in detail to the drawings, a tinning line for steel strip comprises a plurality of electrolyte pans 10a, 10b, etc., spaced apart horizontally and arranged, as shown in Figure 1, in vertically spaced tiers. The pans and other associated apparatus to be described are carried on columns 11a and 11b standing on a suitable foundation 12. The pans of the lower tier are carried on cross beams 13 which rest on girders 14 extending between adjacent columns. Similarly, the pans of the upper tier are carried on cross beams 15 which rest on girders 16 secured to the columns.

Electrolyte is supplied to the pans 10a, 10b, etc., from a sump tank 17 by a pump 18 and delivery pipe 19. The electrolyte delivered to the pans overflows the end walls thereof and falls into collecting trays 20. A drain pipe 21 extends downwardly from the trays 20 to the tank 17. Alternate drain connections 22 are provided for carrying away the electrolyte when it is to be discarded.

In order to supply current to the strip passing successively through the pans, contact rolls 23, 24 are journaled in spaced housings 25 carried on the beams 13. One pair of rolls 23, 24 is disposed between each pair of adjacent pans of both the upper and lower tiers. The rolls are composed of metal but the roll 24 has a rubber sheath 26 covering the exterior of the body portion thereof. The rolls have reduced necks journaled in suitable chucks disposed in the housings 25. A top transom 27 (shown in chain lines as having been removed) connects the upper ends of the housings in which opposite ends of the rolls of each pair are journaled. Keeper yokes 27a secured to the transom extend downwardly therefrom around the necks of roll 23. The transom is also provided with screwdowns 27b. As shown in Figure 2, the pass line 28 between the rolls is only slightly above the edges of the end walls of the pans so that strip traveling between the rolls is in contact with the electrolyte delivered to the pans and overflowing the end walls thereof.

Anode bars 29 of tin are disposed in the pans below the path of the strip. Connections thereto from one terminal of the source of electric cur-

rent are established by any suitable means. The rolls 23 establish connections from the strip to the other terminal of the current source. Brush holders 30 are secured to, but insulated from, the housings 25 and are provided with fixed brush arms 31. Swinging brush arms 32 are also carried on the holders 30. The brush arms are provided with a plurality of brushes 33 adapted to engage enlargements 34 on the necks of roll 23. Conductors of any suitable form extend from the brush holders 30 to the other terminal of the source of electric current.

The means which I have invented for quickly removing the upper contact roll 23 includes an overhead rail 35 secured to the girders 16 intermediate the columns 11a and 11b between adjacent pans 10a, 10b, etc., and a trolley 36 adapted to travel thereon. As clearly shown in the drawings, the rail 35 extends transversely of the tinning line and to points laterally thereof which are relatively free from overhead obstruction. The trolley 36 has a hoist 37 thereon adapted to lift the roll 23 by means of a sling 38.

When it is desired to replace a contact roll 23 for the purpose of redressing it to remove accretions of tin adhering thereto after a period of service, the brush arms 32 are thrown back as shown in Figure 2 and the transom 27 is removed. Since the keeper yokes 21a and screwdowns 21b come out with the transom, the removal of the latter leaves the bearing chucks on the extreme ends of the roll necks free for upward movement. The sling 38 is then placed around the roll body and the trolley 36 is run in on the rail 35 to the position shown in solid lines in Figure 1. The hoist is then operated to raise the roll 23 to position A shown in chain lines in Figure 1. The trolley 36 is then run out on the rail 35 to position B shown in chain lines in Figure 1. The roll is then lowered onto any suitable support disposed alongside the tinning line, being thus positioned at a point relatively free from overhead obstruction where it may be picked up by the mill crane.

A redressed roll previously made ready may then be lifted by the hoist to position B and the trolley 36 run back into solid line position so that the new roll, suspended in position A, may be directly lowered into place in the housings 25. Replacement of the transom 27 is all that remains in order to permit the tinning line as a whole to resume operation.

The advantages of my invention will be readily appreciated from the fact that in an ordinary tinning line, there may be as many as twenty or more electrolyte pans and a pair of contact rolls between each pair of adjacent pans. Since the upper or conducting contact roll requires redressing about once a week, as above indicated, it will be perceived that twenty or more roll changes will be required every week and that the total time lost from stoppages of the line for roll changing is materially reduced by the invention which makes possible the changing of the rolls in a minimum time. The rolls of the upper tier may be provided with handling equipment similar to that described for the rolls of the bottom tier since access thereto by the usual mill crane is obstructed by other electro-coating apparatus such as rinse tanks installed thereabove. My invention avoids the prolonged stoppages of production which have heretofore been necessary for the purpose of changing the contact rolls of both the bottom and top tiers by hand. It will be understood that the rail 35 and trolley 36 are

duplicated between each pair of electrolyte pans of the two tiers.

While the invention has been described in connection with the changing of the contact rolls of a tinning line, it is obviously applicable to similar apparatus for plating strip with a coating of zinc or other metal, as well as to other installations of the same general type in which overhead obstructions interfere with the handling of a roll by the usual mill crane.

Although I have illustrated and described but a preferred embodiment of the invention, it will be recognized that changes in the construction and arrangement disclosed may be made without departing from the principle of the invention or the scope of the appended claims.

I claim:

1. Lifting apparatus for use in an electrolytic coating line or the like wherein electrolyte pans are disposed in vertically spaced tiers and contact rolls are disposed between adjacent pans and journaled in spaced housings, the parts in the upper tier precluding the use of a mill crane for handling the rolls of the lower tier, said apparatus comprising a hoist and a rail on which it travels, said rail being below the pans and rolls of the upper tier and extending above a set of rolls in the lower tier and laterally thereof to a point relatively free from overhead obstructions.

2. Apparatus for changing rolls in an electrolytic coating line wherein a series of electrolyte pans are disposed in vertically spaced tiers and carried on common supporting columns, and contact rolls are disposed between adjacent pans in each tier, and journaled in spaced housings, precluding the use of a mill crane for handling the rolls of the lower tier, said apparatus comprising an overhead rail supported by said columns extending transversely of the line and laterally thereof to a point relatively free from overhead obstruction, and a trolley having a hoist thereon traveling along said rail.

3. Lifting apparatus for use in an electrolytic coating line or the like wherein pans are disposed in vertically spaced tiers and contact rolls are positioned adjacent one or more of said pans, the arrangement of pans and rolls precluding the use of a mill crane for handling the rolls in one of said tiers below the uppermost tier, said apparatus comprising a hoist and a rail on which it travels, said rail being below the uppermost pan and extending above a set of rolls adjacent a lower pan and laterally thereof to a point relatively free from overhead obstructions.

4. Lifting apparatus for use in an electrolytic coating line or the like wherein pans are supported by framework in vertically spaced tiers and contact rolls are positioned adjacent one or more of said pans, the arrangement of pans and rolls precluding the use of a mill crane for handling the rolls in one of said tiers below the uppermost tier, said apparatus comprising a hoist and a rail on which it travels, said rail being supported by said framework and extending from a point above a set of rolls adjacent a lower pan to a point relatively free from overhead obstructions.

5. In combination, framework having a plurality of levels, electro-coating apparatus supported by the framework at each of said levels, said apparatus in at least one of said levels including contact rolls, a rail supported by the framework over the roll and extending beyond the framework to a point relatively free from overhead obstructions, and a hoist on said rail.

CLARENCE J. KLEIN.
